UNITED STATES PATENT OFFICE.

KARL FREDERICK MARX, OF DETROIT, MICHIGAN.

MACHINE FOR TURNING CRANK PINS OF CRANK SHAFTS.

Application filed November 22, 1920. Serial No. 425,870.

To all whom it may concern:

Be it known that I, KARL FREDERICK MARX, a citizen of the United States, residing at 4726 Belvidere Ave., Detroit, in the county of Wayne and State of Michigan, have invented a new and useful Machine for Turning Crank Pins of Crank Shafts, of which the following is a specification.

My invention relates to a new machine in which a multiple throw crankshaft to be machined by tools of tool carrying crank shafts, having the same length of stroke as the former, so that all of said crankshafts run in parallelism, and the object of my invention is, to provide a machine for turning all crank pins of a multiple throw crank shaft at the same time by revolving said crankshaft around its main axis and not as in the old way around its crank pin axes, thereby saving considerable time in machining and cost of operation. I attain the above and other objects by the mechanism illustrated in the accompanying drawings, in which—

Fig. 1 is a vertical section of the entire machine on the line 1—1 Fig. 2.

Fig. 2 a plan of the machine, and

Fig. 3 a vertical section of a part of the machine on line 3—3 Fig. 2, as it appears after the removal of the tool holders.

Similar numerals refer to similar parts throughout the several views. A main frame 3, its base or standard 1, and an oil pan 2, secured to the underside of the main frame, constitute the framework of the machine. Slidable on ways of the frame 3 is a carriage 4 operated by feed screw 5 and hand wheel 28. In the carriage 4 rotates a multiple throw crankshaft 6 around its main axis 21, said crank shaft being held in alignment by chucks 31 and 39, and driven by gears 12. Idlers 13 driven by main drive pinion 14 on a drive shaft 29, form a connection between gears 12 and gears 15, the latter driving one of the tool carrying crankshafts 8, and in turn, being connected by idlers 16 on a shaft 18, with gears 17 driving the other tool carrying crank shaft 9.

As all three gears 12, 15 and 17 have the same number of teeth, all crankshafts will rotate in the same direction in parallelism to each other around their respective axes 12, 22 and 37, provided they are secured to said gears parallel to each other. By this

arrangement it is possible to keep cutting tools 19 and 20, which are inserted in angular tool holders 10 and 11 carried by bearings 32, 33, 34 and 35 on the crank shafts 8 and 9, in proper relation to the crank shaft 6. As the tool carrying crank shafts are rotatable in bearings 38 of a housing 7 best shown in Fig. 3, it is possible to tilt said housing 7 about an axis 22 by means of a swivel nut 30, cross feed screw 23 operated by hand wheel 27, and bevel gears 24, 25 and 26 held by swinging bracket 40, and stationary bracket 36, thereby causing the tools 19 and 20 to approach or deviate from the crank pins to be machined as the operator sees fit. Of course instead of being hand operated, means for automatic operation can be incorporated in the lateral and longitudinal feed mechanism of the machine.

I am aware that prior to my invention, crank pin turning lathes have been made with the crankshaft revolving around the axis of the crank pin to be turned, whereas, in my invention, the crankshaft revolves around its main axis, therefore I claim:

1. In a metal working machine, means for causing a piece of work to move in a circumferential path, a tool, an angular tool holder having a short arm and a long arm with the tool at the juncture of said arms, and means engaging an end of each arm of said angular tool holder for maintaining said holder vertical and for causing said tool in its holder to travel in a circumferential path having an eccentric relation to the first mentioned path so that the tool may constantly operate upon the piece of work.

2. A machine of the type described comprising a tiltable housing, means for tilting said housing, crank shafts journaled in said housing one above the other, angular tool holders on said crank shafts, tools carried by said holders, and means for supporting another crank shaft for operation in synchronism with said crank shafts so that said tools may operate on said crank shaft.

3. A machine of the type described comprising upper and lower crank shafts, angular tool holders on said crank shafts, tools carried by said tool holders, means for supporting another crank shaft for operation in synchronism with said crank shafts so

that said tools may operate on said crank shaft, and means adapted for bodily tilting the first mentioned crank shafts.

4. A machine of the type described comprising upper and lower crank shafts, angular tool holders on said crank shafts, tools carried by said tool holders, and means for

supporting a third crank shaft in the horizontal plane of the upper crank shaft for operation in synchronism with said upper and lower crank shafts so that said tools may operate on said third crank shaft. ¹⁰

KARL FREDERICK MARX.
